REFRIGERATING MACHINE

Christian Steenstrup, Schenectady, N. Y., assignor to General Electric Company, a corporation of New York

Application June 29, 1935, Serial No. 29,036

14 Claims. (Cl. 62—115)

My invention relates to refrigerating machines. It is an object of my invention to provide a refrigerator comprising a cabinet and a refrigerating machine of the type including a motor 5 and a compressor arranged within a closed casing and having an improved arrangement for supporting the casing, and a refrigerant condenser, the support being utilized to provide efficient dissipation of heat from the condenser.

10 Further objects and advantages of my invention will become apparent as the following description proceeds, and the features of novelty which characterize my invention will be pointed out with particularity in the claims annexed to 15 and forming a part of this specification.

For a better understanding of my invention reference may be had to the accompanying drawing in which Fig. 1 shows a household refrigerator provided with a refrigerating machine embodying my invention, and Fig. 2 is an enlarged 20 sectional elevation view of the refrigerating machine shown in Fig. 1, portions thereof being shown in full for the sake of clearness.

In accordance with my invention, I provide a 25 heat insulated cabinet and a refrigerating machine comprising a motor and compressor casing supported on a base and a refrigerant condenser secured in heat exchange relation with the walls of the base, so that heat may be removed from the condenser by convection currents of air passing over the outer walls of the base, and so that the casing provides a smooth 30 surface which rapidly radiates heat, and which is also cooled by convection currents.

35 Referring now to the drawing, in Fig. 1 I have shown a refrigerator embodying my invention including a cabinet 10 having a door 11 and provided with a refrigerating machine comprising a base 12 forming a removable top wall of the 40 cabinet, a spherical casing 13 having a motor and a compressor arranged therein, and a refrigerant evaporator 14 for cooling the interior of the cabinet 10.

As shown in Fig. 2, the casing 13 is constructed 45 of upper and lower hemispherical portions secured together by welding a seam at 13a around their line of contact, a band 13b arranged inside the casing and overlapping the two portions of the casing at the line of welding being provided to reinforce the seam. A band 13c of stainless steel or other suitable finishing material is secured over the seam 13a in order to give a 50 pleasing appearance. The base 12 is made of sheet metal and comprises a sheet metal top wall 55 15 and a sheet metal side wall constructed of

inner and outer metal sheets 16 and 17 respectively secured together face to face, the sheet 17 having indentations or corrugations therein providing a condenser 18 formed in the walls of the housing. The sheets 16 and 17 are welded together entirely about their edges and closely adjacent the opposite sides of the indentations throughout their length. The upper wall 15 has an annular upturned flange 19 having a downturned lip 20 to which the lower portion of the 10 casing 13 is secured by welding, brazing or in any other suitable manner, and is thereby maintained in good heat exchange relation with the casing. The top wall 15 is provided with a downturned flange 15a welded to the upper edge of the side 15 wall 17. The base is strengthened by wooden braces 23 around the lower edges of the side walls and a center brace 29 having its ends resting on the braces 23 and secured between the upper portions of two of the side walls near the center of 20 the base. A sheet metal bottom wall 21 is provided for the base and is secured to the base by strips 22 of wood, or other suitable heat insulating material, which insulates the wall 21 from the sides of the base and the outer wall of the 25 cabinet. The strips 22 are secured to the bottom wall by screws 23 and to the side wall of the base by screws 24 extending through an inturned flange 25 on the inner sheet 16 and into the 30 braces 23. A gasket 26 of rubber or other resilient material is secured between the strips 22 and the outer sheet 17 of the side wall of the base and provides a seal between the base and the cabinet 10 when the base has been placed on the cabinet. The wall 17 fits over the side wall of the cabinet 35 10 so that the base 12 forms a continuation of the cabinet wall. A body of heat insulating material 27 fills the space within the base above the bottom wall 21 and constitutes the top wall 40 insulation of the cabinet. A float valve chamber 45 or liquid refrigerant receiver 30 is arranged within the base and is surrounded by the body of heat insulation 27. The bottom wall 21 supports the evaporator 14 which is secured to the lower side thereof by bolts 31.

A motor 32 is arranged to drive a compressor 33, which is secured to the upper portion of the frame of the motor, and this motor and compressor unit is resiliently mounted within the casing 13 on springs 32a. This arrangement for 50 mounting the motor and compressor within the refrigerant casing is not my invention but is the invention of Harley H. Bixler and is described and claimed in his Patent No. 2,028,584, granted January 21, 1936, and assigned to General Elec- 55

tric Company, assignee of my present invention. I do not, therefore, herein claim anything described or claimed in the said Bixler patent which is to be regarded as prior art with respect to the present application, my invention relating to an improved arrangement for mounting the casing and the condenser.

During operation of the refrigerating machine the compressor 33 withdraws refrigerant from the 10 interior of the casing 13 and pumps it through an outlet connection 34 into a muffle box 35 and thence through a conduit 36 into the condenser 18. Gaseous refrigerant pumped into the condenser 18 is at a relatively high temperature due 15 to the compressing operation, and the air on the outside of the base 12 about the condenser 18 flows upwardly continuously carrying away the heat of the refrigerant. The refrigerant is thus cooled and is liquefied, and the liquid refrigerant 20 flows from the condenser through a connection 37 into the receiver or float valve chamber 30. When a predetermined amount of refrigerant is collected in the chamber 30, a float therein rises and opens a valve, which permits the refrigerant 25 to flow through a connection 38 into circulating passages 39 of the evaporator. Liquid refrigerant within the evaporator 14 is vaporized by the absorption of heat from the air within the cabinet 10 and from articles such as freezing trays placed 30 in the evaporator, and the vaporized refrigerant collects in a header 40 from which it is withdrawn through a suction conduit 41 and returns to the casing 13.

In order adequately to lubricate the motor and 35 compressor and also to cool them, I provide an oil pump driven by the motor 32 and having an intake 42 opening into a body of oil 43 in the bottom of the casing 13. When the motor 32 is in operation oil is pumped from the bottom of the casing 40 through the working mechanism of the motor and compressor and is discharged through a nozzle 44 against a bulge 45 in the top of the casing 13. The bulge 45 causes the oil to flow evenly over the inner surface of the casing where it is cooled, 45 the heat being dissipated by radiation and by convection currents of air flowing over the outside of the casing 13 the major portion of which is above the housing 12. A baffle 46 arranged near the top of the casing 13 is provided to collect oil 50 which may drop down toward the motor 32 and to carry the oil to the side of the casing, openings 55 47 being provided in the baffle to permit the oil to flow through the baffle. Since the oil is continuously pumped through the motor and compressor and over the sides of the casing 13 the body of oil at the bottom of the casing is maintained relatively cool, and the heat of the motor and compressor is continuously dissipated. This arrangement of the oil circulating system including 60 the baffle 46 and the bulge 45 is described and claimed in my copending application, Serial No. 1,319 filed January 11, 1935 and assigned to General Electric Company, assignee of my present invention.

65 During operation of the refrigerating machine described herein the condenser is continuously cooled by radiation and by the convection currents of air circulating about the walls of the refrigerator cabinet. The circulation of air is 70 free and uninterrupted and results in efficient cooling of the condenser. The motor and compressor are also efficiently cooled by the dissipation of heat by radiation, and also by convection currents circulating about the spherical casing. 75 It is to be noted that the casing constructed as

shown and having no fins or other projections thereon permits radiation of heat in all directions and with a minimum of re-radiation from adjacent surfaces. The spherical form of the casing provides a very efficient radiating surface, which 5 is easily cleaned, has a pleasing appearance, and is economical to manufacture.

While I have described my invention as applied to a household refrigerating machine, modifications thereof will occur to those skilled in the art. 10 I do not, therefore, desire my invention to be limited to the particular construction shown and described, and I intend in the appended claims to cover all modifications within the spirit and scope 15 of my invention.

What I claim as new and desire to secure by Letters Patent of the United States is:

1. A refrigerator comprising a cabinet having insulated side and bottom walls, a refrigerating machine for cooling the interior of said cabinet, 20 said refrigerating machine including a closed casing having a gaseous refrigerant therein, means including a sheet metal base having top and side walls and constituting a removable top wall of said cabinet for supporting said casing, means 25 for providing a refrigerant condenser utilizing said base as a heat dissipating surface, means including a motor and a compressor in said casing for pumping gaseous refrigerant from said casing to said condenser, a body of heat insulating material within said base, means including a bottom wall for said base thermally insulated from said side walls for enclosing said body of heat insulating material within said base, and a refrigerant 30 evaporator for said machine arranged within said 35 cabinet.

2. A refrigerator comprising a cabinet having insulated side and bottom walls, a refrigerating machine for cooling said cabinet, said refrigerating machine including a closed casing having a 40 gaseous refrigerant therein, means including a sheet metal base having top and side walls and constituting a removable top wall of said cabinet for supporting said casing, said base being arranged in heat exchange relation with the lower 45 portion of said casing to dissipate heat from said casing, means for providing a refrigerant condenser utilizing a wall of said base as a heat dissipating surface, means including a motor and a compressor in said casing for pumping gaseous 50 refrigerant from said casing to said condenser, a body of heat insulating material within said base, means including a sheet metal bottom wall for said base thermally insulated from said side walls 55 for enclosing said body of heat insulating material within said base, and a refrigerant evaporator for said machine arranged within said cabinet.

3. A refrigerator comprising a cabinet having insulated side and bottom walls, a refrigerating machine for cooling said cabinet, said refrigerating machine including a closed casing having a gaseous refrigerant therein, means including a sheet metal base having top and side walls and constituting a removable top wall of said cabinet for supporting said casing, said side walls of said 60 base comprising continuations of the side walls of said cabinet, said base being arranged in heat exchange relation with the lower portion of said casing to dissipate heat from said casing, a refrigerant condenser for said machine formed 65 within the wall of said base and utilizing said wall as a heat dissipating surface, means including a motor and a compressor in said casing for pumping gaseous refrigerant from said casing to said condenser, a body of heat insulating material 70 75

within said base, means including a sheet metal bottom wall for said base thermally insulated from said side walls for enclosing said body of heat insulating material within said base, and a refrigerant evaporator for said machine arranged within said cabinet.

4. A refrigerator comprising a cabinet having insulated side and bottom walls, a refrigerating machine for cooling said cabinet, said refrigerating machine including a closed spherical casing having a gaseous refrigerant therein, means including a sheet metal base having top and side walls constituting a removable top wall of said cabinet and secured in heat exchange relation with said casing for supporting said casing, means for providing a refrigerant condenser for said machine utilizing said base as a heat dissipating surface, said condenser being arranged to be cooled substantially entirely by air circulating over the outside only of said base, means including a motor and a compressor in said casing for pumping gaseous refrigerant from said casing to said condenser, a bottom wall for said base thermally insulated from said side walls, and a refrigerant evaporator for said machine arranged within said cabinet.

5. A refrigerator comprising a cabinet having insulated side and bottom walls, a refrigerating machine for cooling said cabinet, said refrigerating machine including a closed spherical casing having a gaseous refrigerant therein, means including a sheet metal base having top and side walls constituting a removable top wall of said cabinet and secured in heat exchange relation with said casing for supporting said casing, said side walls of said base comprising continuations of the side walls of said cabinet, means for providing a refrigerant condenser for said machine utilizing said base as a heat dissipating surface, said condenser being arranged to be cooled substantially entirely by air circulating over the outside only of said base, means including a motor and a compressor in said casing for pumping gaseous refrigerant from said casing to said condenser, a bottom wall for said base thermally insulated from said side walls, and a refrigerant evaporator for said machine arranged within said cabinet.

6. A refrigerating machine including a closed casing, a motor and a compressor arranged in said casing, means including a sheet metal base arranged below said casing for supporting said casing, means for providing an air cooled condenser for said machine utilizing said base as a heat dissipating surface, a body of heat insulating material within said base, means including a thermally insulated bottom wall in said base for enclosing said body of heat insulating material within said base, means including a receiver arranged within said body of heat insulating material for collecting liquid refrigerant from said condenser, and a refrigerant evaporator for said machine.

7. A refrigerating machine including a closed casing having gaseous refrigerant therein, means including a sheet metal base having top and side walls and secured to the lower portion of said casing for supporting said casing, means for providing an air cooled refrigerant condenser for said machine utilizing said base as a heat dissipating surface, means including a motor and a compressor in said casing for pumping gaseous refrigerant from said casing to said condenser, a body of heat insulating material within said base, means including a bottom wall for said base thermally insulated from said side walls for enclosing

said body of heat insulating material within said base, and a refrigerant evaporator for said machine.

8. A refrigerating machine including a closed casing having gaseous refrigerant therein, means including a base having top and side walls and secured to the lower portion of said casing for supporting said casing, means for providing an air cooled refrigerant condenser for said machine utilizing said base as a heat dissipating surface, means including a motor and a compressor in said casing for pumping gaseous refrigerant from said casing to said condenser, a body of heat insulating material within said base, means including a bottom wall for said base thermally insulated from said side walls for enclosing said body of heat insulating material within said base, a refrigerant evaporator for said machine, and means including a receiver and a float valve therein arranged within said body of heat insulating material for controlling the flow of refrigerant from said condenser to said evaporator.

9. A refrigerating machine including a closed casing having gaseous refrigerant therein, means including a sheet metal base having top and side walls and arranged in heat exchange relation with the lower portion of said casing for supporting said casing, a refrigerant condenser formed within the walls of said base in heat exchange relation therewith, means including a motor and a compressor in said casing for pumping gaseous refrigerant from said casing to said condenser, a body of heat insulating material within said base, means including a bottom wall for said base thermally insulated from said side walls for enclosing said body of heat insulating material within said base, a refrigerant evaporator for said machine, and means including a receiver and a float valve therein arranged within said body of heat insulating material for controlling the flow of refrigerant from said condenser to said evaporator.

10. A refrigerating machine including a closed casing having gaseous refrigerant therein, means including a sheet metal base having top and side walls and arranged in heat exchange relation with the lower portion of said casing for supporting said casing, said side walls of said base comprising two sheets of metal secured together face to face, means including indentations formed in one of the sheets of said side walls for providing a refrigerant condenser in said side walls, means including a motor and a compressor in said casing for pumping gaseous refrigerant from said casing to said condenser, a bottom wall for said base, and a refrigerant evaporator for said machine.

11. A refrigerating machine including a closed casing having gaseous refrigerant therein, means including a base having top and side walls and arranged in heat exchange relation with the lower portion of said casing for supporting said casing, the top wall of said base having an opening therein and the lower portion of said casing extending partially through said opening, means for providing an air cooled refrigerant condenser utilizing said base as a heat dissipating surface, means including a motor and a compressor in said casing for pumping gaseous refrigerant from said casing to said condenser, a bottom wall for said base, and a refrigerant evaporator for said machine.

12. A refrigerating machine including a closed spherical casing having gaseous refrigerant therein, means including a base having top and

- side walls and secured to the lower portion of said casing for supporting said casing, means for providing an air cooled refrigerant condenser utilizing said base as a heat dissipating surface, means including a motor and a compressor in said casing for pumping gaseous refrigerant from said casing to said condenser, a bottom wall for said base thermally insulated from said side walls, and a refrigerant evaporator for said machine.
- 5 13. A refrigerating machine including a closed spherical casing having gaseous refrigerant therein, means including a base having top and side walls and arranged in heat exchange relation with the lower portion of said casing for supporting said casing, said base having an opening therein and said casing extending therethrough, the major portion of said casing being above the top wall of said base, means for providing an air cooled refrigerant condenser utilizing said base as a heat dissipating surface, means including a motor and a compressor in said casing for pumping gaseous refrigerant from said casing to said
- 10 15

condenser, a bottom wall for said base thermally insulated from said side walls, and a refrigerant evaporator for said machine.

14. A refrigerating machine including a closed spherical casing having gaseous refrigerant 5 therein, means including a base having top and side walls and arranged in heat exchange relation with the lower portion of said casing for supporting said casing, said top wall of said base having a circular opening therein and an annular flange 10 about said opening, said spherical casing being positioned by said flange and being secured thereto, means for providing an air cooled refrigerant condenser, utilizing said base as a heat dissipating surface, means including a motor and a 15 compressor in said casing for pumping gaseous refrigerant from said casing to said condenser, a bottom wall for said base thermally insulated from said side walls, and a refrigerant evaporator for said machine. 20

CHRISTIAN STEENSTRUP.
